G. H. FRASER,
APPARATUS FOR TREATING PULVERIZED MATERIAL.
APPLICATION FILED AUG. 17, 1918.

1,385,675.

Patented July 26, 1921.

UNITED STATES PATENT OFFICE.

GEORGE HOLT FRASER, OF BROOKLYN, NEW YORK.

APPARATUS FOR TREATING PULVERIZED MATERIAL.

1,385,675.

Specification of Letters Patent. Patented July 26, 1921.

Original application filed September 25, 1912, Serial No. 722,233. Divided and this application filed August 17, 1918. Serial No. 250,279.

To all whom it may concern:

Be it known that I, GEORGE HOLT FRASER, a citizen of the United States, residing in the borough of Brooklyn, county of Kings, 5 city and State of New York, United States of America, have invented certain new and useful Improvements in Apparatus for Treating Pulverized Material, (being a division of my application filed September 10 25, 1912, Serial No. 722,233,) of which the following is a specification.

This invention relates to means for treating finely divided material, or mixtures of various pulverized substances, and to grinding, screening and mixing the same, and aims 15 to provide improved means especially applicable to carrying out the improved methods set forth.

Heretofore it has been common to pulverize mixed materials of different physical characteristics or different specific gravity, to grade the material according to size so that that material too large for pulverizing should be separated from that to be fed to 20 the pulverizer, and that sufficiently pulverized material should be separated for subsequent treatment. Ordinarily a coarse screen or grizzly is used to remove the coarsest material, and a fine screen or air 25 separator is used to extract the powder, the intermediate material being returned to the pulverizer for further screening. The coarse screen is used to prevent the coarser 30 material from wearing the finer separator, and its product may be mixed with the reject of the latter for return to the pulverizer 35 after the fine separator has operated on the material.

The coarse material or mixture is supplied from a bin or suitable source, and the fine material is removed as made to a bin or suitable discharge. The various successive operations are effected by suitable apparatus arranged in the desired order and 45 connected by any usual means for delivering from one to another.

In such operations difficulties have arisen from the liability of the mixture to change in proportions at different times, especially 50 when one ingredient is lighter than another or of different physical characteristics. This changing of the relative percentages of the different materials in the mixture affects the chemical qualities of the mass, and where subsequent chemical treatment is required it is very disadvantageous.

In pulverizing, difficulty sometimes results from the liability of material of intermediate fineness occurring in irregular quantities, and variations in the proportions of coarse material and intermediate material injuriously affect the operation of the apparatus, as well as causing variations in the proportions of the mixture.

This invention aims to provide a method whereby material can be pulverized and separated with more economy of space and power than heretofore and without materially altering the character of the mixture, whereby pulverization can be effected with greater uniformity, and whereby the operation of pulverizing and separating material may be automatically regulated by the material being treated.

It also aims to provide improved apparatus for pulverizing, separating and treating finely divided material or mixtures.

To this end in carrying out the preferred form of the improved process, the pulverized material is withdrawn from the pulverizer with the intermediate material by gravity as fast as discharged and is immediately separated and removed as finished in quantities corresponding with the quantities of fresh material introduced for treatment, the proportions being continuously maintained so that the material under treatment shall always be under uniform conditions, and the introduction of new material is automatically controlled by the presence of intermediate material, so that while intermediate material is present in the system to the desired extent, the supply of fresh material is controlled by it to the extent desired to insure the finishing of the intermediate material present before ingress of fresh material. The escaping finished material controls the supply of fresh material, and the intermediate material present only is elevated and refed to the pulverizer, and this refed material regulates the entrance of fresh material. The effect of this is that the quantity of material being treated is maintained so uniformly that substantially the same conditions prevail throughout treatment, and its treatment must be completed before additional material can enter, thus precluding important changes.

in the percentages of the materials constituting the mixture, since the charge under treatment must be disposed of before additional material can be treated, while the material as finished is continuously withdrawn and is continuously replaced by the automatic control of the fresh supply, and any unnecessary lifting of finished material is avoided.

- 10 Where the separation of finished material is effected by a fluid current or air separator and the materials differ greatly in specific gravity, this precaution against changing of the mixture is especially important, as in such instances the air separation would tend to remove the lighter material from the heavier regardless of fineness, in case a continuing supply of material were available before all of the material present had been pulverized.

15 This invention also provides improved means for carrying out the improved process, which means preferably comprise a pulverizer, a coarse screen, a fine separator, a supply bin, an elevator, and means connecting these parts in succession to effect the desired results.

20 In the accompanying drawings Figure 1 shows the preferred utilization of the improved process, and the preferred embodiment of the improved apparatus, and is a vertical axial section of a pulverizing, screening, separating, feeding, elevating, and discharging system, especially applicable for carrying out these improvements, the view being cut approximately on the line 1-1 of Figs. 2 and 3 looking in the direction of the arrows; Fig. 2 is a fragmentary vertical section thereof cut at right angles to Fig. 1 approximately on the line 2-2 of Fig. 3 and looking in the direction of the arrows, and Fig. 3 is a fragmentary horizontal section thereof cut approximately on the line 3-3 of Fig. 2 and looking in the direction of the arrows.

25 Referring to the drawings, A indicates a pulverizer, B is a drive pulley therefor, C the grinding chamber thereof, D the discharge conduit, E the inlet conduit thereof, F a coarse screen, G its tailings spout, H an air separator, I its tailings spout, J its fine chamber, K its fine spout, L the fine discharge, M the coarse rock supply or feed bin, N the feed hopper, O the feed regulating or controlling chamber, P the elevator or other means communicating between the parts O and E, and Q the supply regulator.

30 The parts of the device shown may be of any suitable or usual construction and connected in any desired order or manner, but it is preferred to use a pulverizer of the ring and roll type in which the crushing members revolve on horizontal axes within the crushing chamber, and in which the material is centrifugally carried by the ring

and free to discharge in a vertical plane therefrom regardless of the fineness of the material, and to drive the pulverizer from a suitable source of power, and to drive the other parts from the pulverizer, connecting the parts in succession so that the operation of all will be coincident.

35 As shown, the coarse screen or grizzly immediately succeeds the pulverizer, and is disposed below the latter to receive the discharge therefrom, having a revolving distributing disk R on which this discharge falls and by which it is spread horizontally or thrown centrifugally to the outer edge of the screen, which latter is a vibratory non-rotative member.

40 It is preferable to construct the screen in the shape of an inverted cone elastically suspended from above by a spring S, so that it may descend under load or shock and will rise when released, and its upward movement will be suddenly arrested to give it a vibration or upward bump to jar material out of its meshes. A lever or arm T hinged to the casing a above the screen and in the path of a projection on the disk R serves to depress the screen when struck by the disk, thus vibrating the screen.

45 Preferably the screen is provided with swinging or spring strikers U, shown as both extending toward the shaft V of the disk R and movable into the path of swinging hammers W thereon, so that they will be struck thereby when the screen is depressed to agitate it for cleaning.

50 The screen F is preferably extended within and discharges its fines onto the inner face of a revolving spreader or distributor X, which is preferably an inverted cone mounted on and revolving with the shaft V, and having an outlet surrounding and spaced apart from the outlet of the screen F. The distributor X revolves with sufficient speed to raise and distribute over its upper edge the material fine enough to pass the screen F, which material is thrown or spread horizontally against a deflector Y, from which it falls onto the receiving cone Z of the air separator, crossing the outlet thereof, so that the outflowing current can blow the powdered material of desired fineness out of the falling material and into the settling or extracting chamber J of the air separator, the air from which returns within the apron b, over the tailings cone c, through the outlet d of the receiving cone, which parts afford between them inner and outer current passages, to the blades e of the blower f, which latter is preferably a conical wall surrounding the cone distributor X, and revolving therewith, and having radial blades between its inner face and the adjacent face of the distributor. The receiving cone Z is yieldingly supported by springs g so that it can be depressed until

its inner projections *h* are brought into the path of revolving strikers *i* to jar it.

The tailings cone *c* communicates with the cylindrical upper end of the spout *I*, which 5 end surrounds and is concentric of the coarse spout *G*, which latter receives the coarse material from the coarse screen *F*. The distributor or cone *X* has bottom outlets *j* for any material failing to rise in the distributor, so that this material may drop 10 through the bottom of the distributor and into the receiving cone *Z* and flow by gravity through the bottom outlet *d* thereof to the spout *I*. All material too large to be floated 15 through the outlet, slides by gravity down the receiving cone *Z* and escapes through its outlet to the spout *I*.

The spout *G* discharges by gravity above and preferably vertically down into the regulating chamber *O*. If it is desired to use 20 the material flowing through the spout *I*, instead of to further grind it, the door *k* in the bottom of this spout is turned up as shown in full lines so as to let the material 25 in the spout *I* escape through the chute *l*, but if this material is to be reground, this door is closed as shown in dotted lines and the material enters the regulating chamber with the coarse material from the spout *G*. 30 The regulating chamber *O* discharges its material by gravity through a bottom outlet *m* to the boot of the elevator *P*, which raises the material to the feed inlet *E*, so that there is an endless circuit communicating through 35 the pulverizer, the screen, the separator, and the elevator back to the pulverizer, through which the coarse reject from the screen and the intermediate reject from the separator may be continually re-fed to the pulverizer 40 without the necessity of also lifting the finished material, so that this material will be re-fed for re-grinding with the minimum of lifting power expenditure.

The fine material settling in the dust chamber *J* flows into its spout *K* and escapes therefrom to the fine bin *L*.

The fresh feed from the chamber *M* flows past a gate *n* and a rock crusher or crushing roll *o* to the feed chamber *N*, from which 50 it passes through outlets *p* to the regulating chamber *O*. These outlets preferably have adjustable lips *q* within the chamber *O* which extend inwardly, so that the angle from the top of the outlet *p* to the edge of 55 the lip or shelf *q* is adjustable to control flow of the material escaping from the feed bin. The feed bin surrounds one or more sides of the regulating bin and has several outlets thereto, preferably one on each of 60 two sides, for example as shown in the drawings wherein the chamber or bin *O* is shown as a vertically extending pipe or tubular member having an imperforate wall opposite each outlet *p* from the fresh feed hopper *N*, the openings *p* entering the bin *O*

laterally intermediate of its bottom outlet *m* and its upper superposed fine and coarse tailings inlets *L* and *G*.

The regulating bin is similar to a vertical conduit chute, and its inlet for intermediate and coarse material is above the inlets for fresh material, and its outlet is below these inlets. The intermediate material falls into the regulating chamber, and if it is not removed through the outlet therefrom 70 by the elevator as rapidly as it enters, it fills up this chamber until it rises above the outlets *p* of the feed bin, whereupon the intermediate material in front of these outlets arrests flow of fresh material from the feed 75 bin, which it does by closing the outlets therefrom. The removal of the intermediate material below these outlets permits this flow to automatically occur until it has sufficiently filled the regulating chamber to again 80 prevent inflow thereto. The removal of material by the elevator through the outlet from the regulating chamber progresses uniformly, and so long as there is any material in the regulating chamber above the 85 fresh feed outlets, entrance of fresh feed is prevented. The supply of intermediate material thus controls ingress of fresh material, and in this manner the continual 90 grinding of intermediate material is insured, 95 so that all intermediate material except the minimum necessary to control fresh feed will continue to be carried through the circuit of the system until it is pulverized before additional fresh material can enter. 100

In this manner it is assured that the charge of material being treated will be finished before more material can enter, and the excessive removal of a lighter ingredient from the mixture by the air separator 105 will be precluded, since the heavier ingredients left in the system will prevent infeed of fresh material until the air separator has removed a sufficient quantity to permit the infeed of fresh material to automatically 110 resume.

Should the escape of finished material be uninterrupted, the entrance of fresh material can be automatically controlled by the arrangement described, but it is preferred 115 to further insure that the fresh material supplied to the system shall accord with the removal of finished material therefrom. This preferably is accomplished by utilizing the weight of fine material removed to control the supply of fresh material to the feed bin, and vice versa. As shown, the finished material spout *K* discharges into a weighing bucket *r* through a gate *s* which is controlled by a weighing device *t*, and this 120 bucket and gate are connected by a lever *u* with a gate *w* and bucket *x* for the feed bin, which are controlled by a weighing device *y*. The bucket *x* is shown as supported from its weighing device by the trip 125 130

4

catch z , so that the gate w is open and fresh material for the feed bin is entering the bucket x . When the desired quantity has entered the bucket its weight tilts the beam until the trip catch releases, whereupon the bucket rapidly falls, closing the gate w to prevent further infeed of fresh material, tilting the lever u to raise the bucket r and open the gate s until its trip catch z engages and supports this bucket, the bucket x dumping and the bucket r closing, all according to any well known method of automatic weighing, of which the parts illustrated are intended to be diagrammatic representations. The bucket x will discharge its weight load of fresh feed into the feed bin N and the bucket r will collect an equal load of finished material from the spout K , after which the operation will be reversed, the bucket r dumping its load into the fine bin L and closing the fine outlet and restoring the bucket x and opening the feed outlet.

As shown, the elevator is driven from the pulverizer by a belt a^1 , and the distributor for the coarse screen and blower for the air separator, as well as the feeder for the fresh rock, are driven by a belt b^1 therefrom, so that all movable parts of the system coincide with the pulverizer in operation, thus assuring stoppage of all in case of stoppage of the pulverizer, which prevents undue accumulation in any part of the system.

In this manner an automatic mechanical uniformity of supply and removal may be attained to prevent variations in operating conditions and minimize resulting changes.

In operating according to my improved process, one or several grades of the treated material, or of the material in process of treatment, will be utilized to control the feed of other grades of material or of fresh material, according to the requirements of the particular process or conditions of use. The coarser material being projected through the intermediate material, will materially reduce the tendency of the material to segregate according to size within the regulating chamber. The control of the fresh or coarse material by the intermediate material will insure the precedence to the latter in treatment, and greatly diminish tendency to variations in the percentage of ingredients in the mixture if a mixed material is being treated.

In using my improved apparatus the circular or conical vibrator movably and yieldingly mounted in the screen will be easily kept from clogging, and being nested or positioned within the conical redistributing disk, will occupy comparatively little space, and the distributing disk being likewise nested within the receiving cone of the air separator, and the blower of the latter being disposed in conical arrangement between the distributing cone and the receiving cone,

will further minimize the space required for these several parts. The revolving striker in conjunction with the yielding and movably mounted receiving cone, will aid in keeping the cone clean, thus reducing the steepness necessary therefor.

It will be seen that this invention provides improvements in processes of treating materials which can be variously and advantageously availed of in whole or in part, and it will be understood that the invention is not limited to the particular details of arrangement, application or use set forth as constituting its preferred adaptation, since it can be employed in whole or in part according to such modifications and in connection with such devices as circumstances or the judgment of those skilled in the art may dictate, without departing from the spirit of the invention; and it will also be understood that the improvements in apparatus this invention provides are not limited to the particular details of construction, arrangement and combination set forth as constituting the preferred form thereof, since these improvements may be used in whole or in part according to such modifications as circumstances or the judgment of those skilled in the art may dictate, without departing from the spirit of the invention.

For example, in practising the improved process any suitable means for communicating between the parts in any desired successive stage may be employed.

While these improvements in apparatus include in their preferred form circular or conical devices nested within one another for compactness, and having annular communicating ducts and contracting annular outlets, it will be understood that it is not essential that these be used in practising parts of the invention, since the elements may be individualized and connected in any suitable arrangement, or any suitable grizzlies or separators may be employed, if desired.

While the regulating hopper or bin is shown as disposed below all the parts and as feeding from its bottom to the mill through the medium of the elevator, and the plurality of hoppers or bins for different grades of material to be fed are shown as beneath the mill, and the feed bin as surrounding the regulating bin, instead of these parts being above the mill and the regulating bin discharging directly into the latter, it will be understood that the arrangement shown is not essential, being preferred for compactness and convenience of access, and that the plurality of bins may be located as desired, and the connections correspondingly arranged to dispose them in any manner so that feed to the pulverizer may be controlled by any of the several grades of material which it is desired shall govern the operation, the bins and their inlets and outlets

being constructed and connected in proper manner to enable the grade of material which is to have precedence to interrupt or control the inflow of the other grade or 5 grades.

What I claim is:

1. In combination, means for producing pulverized material comprising means affording an endless path affording an inlet 10 for material to be pulverized and an outlet for pulverized material and comprising means having a chamber affording a complementary portion of said path and constituting a way for material in said path, 15 means for causing material to circulate through said path, means for withdrawing fine material from said path, means for withdrawing medium material from said path, means for progressing the residue of partially 20 pulverized material in such path and past said inlet, means for supplying through said inlet fresh material to be pulverized, and means for causing such residue of unpulverized material in said path to control 25 inflow through said inlet of such fresh material.

2. In combination, means for producing fine material comprising means affording an endless path affording an inlet for pulverulent material and an outlet for fine material and comprising a separator having a separating chamber affording a complementary portion of said path and constituting a way for material in said path, means for withdrawing medium material from said path, means for causing material to circulate through said path, means for withdrawing fine material from said path, means for progressing a residue of coarse material in said 35 path past said inlet, means for supplying through said inlet additional pulverulent material, and means for causing such residue material in said path to control inflow through said inlet of such additional material.

3. In combination, means affording an endless path for pulverulent material affording an inlet and an outlet and comprising conveying means having a chamber affording a complementary portion of said path and constituting a way for such material in said path, means for causing material to circulate through such path, means for withdrawing from said path a fine portion and a medium portion of such material circulating through said path, means for progressing in said path the residue of such material therein past said inlet, means for supplying through said inlet additional material to said path, and means for causing such residue material in said path to control inflow through said inlet of such additional material.

4. In combination, means affording an endless path for pulverulent material af-

fording an inlet and an outlet and comprising elevating means having a vertically extending chamber affording a complementary portion of said path and constituting a way for such material in said path, means for causing material to circulate through said path, means for withdrawing through said outlet a fine portion and a medium portion of such material from said path, means for progressing the residue of such material in said path past said inlet, means for supplying through said inlet additional material to said path, and means for causing such residue material in said path to control inflow through said inlet of additional material.

5. In combination, means for producing pulverized material comprising means affording an endless path for material to be pulverized, comprising a crushing chamber affording a complementary portion of said path and constituting a way for material in said path, an elevator for elevating material in said path having a vertically extending chamber affording a complementary portion of said path and constituting a way for material in said path, means for causing material to circulate through said path, means for separating fine and medium material from such material in said path, means for affording an outlet for fine material from said path, means in said path between said crushing chamber and elevator affording an inlet to said path for additional material, means for progressing such residue of material in said path past said inlet, means for supplying through said inlet additional material to said path, and means for causing such residue material in said path to control inflow through said inlet of such additional material.

6. In combination, means for separating fine material comprising means affording an endless path for pulverulent material to be separated and comprising a separator having a separating chamber affording a complementary portion of said path and constituting a way for such material in said path, elevating means for elevating material in said path comprising a vertically extending chamber affording a complementary portion of said path and constituting a way for such material in said path, means for causing such material to circulate through said path, means affording outlets for medium and for fine material from said path communicating with said path between said separator and said elevator for withdrawing from said path fine material separated from the material in said path, means affording an inlet to said path between said elevator and said separator, means for progressing the residue of such material in said path past said inlet, means for supplying to said path through said inlet additional pulveru-

- 6
- lent material, and means for causing such residue material in said path to control inflow through said inlet of such additional material.
- 5 7. In combination, means affording an endless path affording an inlet for pulverulent material and an outlet for fine material and comprising elevating means having a chamber affording a complementary portion of said path and constituting a vertically extending way for such material in said path, separating means for separating fine and medium material from the material in said path having a downwardly extending chamber affording a complementary portion of said path and constituting a gravity way for downward flow of material in said path, means for progressing the residue of material in said path by gravity past said inlet
- 10 15 20 25 30 35 40
- for controlling inflow through said inlet, and means for introducing additional material into said path by gravity through said inlet.
8. In combination, means affording an endless path for pulverulent material and comprising elevating means for elevating such material having a vertically extending chamber affording a complementary portion of said path and constituting an upward way for such material in said path, separating means for separating coarse material from such material in said path having a chamber affording a complementary portion of said path and constituting a gravity way for material in said path, means between said elevating means and said separating means affording a conduit for coarse material affording a complementary portion of said path, means for withdrawing from said path separately fine and medium ma-
- material constituting the residue of such material in said path through said outlet, means for progressing such coarse material in said path past said inlet, means for introducing into said path through said inlet additional material, and means for causing such coarse material in said path to control inflow through said inlet of such additional material.
9. In combination, a separator for separating fine material from pulverulent material having an inlet and having an outlet for fine material and having an outlet for medium material and having an outlet for coarser material, an elevator communicating between said latter outlet and said inlet for raising coarser material discharged through said latter outlet and returning it to said inlet, and means for feeding additional pulverulent material to be separated to said separator controlled by the material discharged through said outlet for coarser material.
10. In combination, a separator for separating fine material from pulverulent material having an inlet and having an outlet for discharging fine material and having an outlet for medium material and having an outlet for coarser material, and means for feeding pulverulent material to be separated to said separator controlled by the fine material discharged through said outlet for fine material.
